DUPLEX FACSIMILE

Raymond R. Haugh, Chicago, Ill.

Application September 5, 1939, Serial No. 293,360

4 Claims. (Cl. 178—7.1)

My invention pertains to the transmitting, receiving and recording of two shaded pictures simultaneously over a single wire circuit or a radio carrier wave.

It has been known to the art to which this present invention relates, that a picture can be scanned by a beam of light and a phototube into areas and the light of each scanned area can be converted into electrical signals, or picture signals which are proportional to the intensity of the white and black picture elements and can be transmitted. At the receiving end the electrical impulses or picture signals are reconverted into picture elements, the value of which bears a direct relation to the signalling energy and are assembled in the same order as the original picture. By the term "picture" is included all printed matter, paintings, photographic negatives and the like.

In a facsimile transmitter, receiver and recorder, the long white or black picture areas are not sent as one continuous modulated signal but are converted by the use of a rotating scanning chopper disc, reed light valve, or multivibrator into dot keying. Thus, the scanned picture is resolved into dots or picture elements and each picture is sent as a separate picture signals. The higher the keying frequency the smaller the picture area represented.

One of the new and novel features, of my invention, deals with the breaking up of two pictures into separate elements and to transmit a picture element from one picture and then from the other. In this system every other picture element of each picture is transmitted.

Another novel feature of my invention deals with a new method for modulating a radio carrier wave, with two sets of picture elements and a synchronizing signal. For example, the alternations on one side of an alternating current are modulated by the light and dark areas of one picture, the alternations on the other side of the said alternating current are modulated by the light and dark areas of the other picture. The peaks of these modulated alternations are suppressed to the same level, leaving only the width of the alternations to represent the light and dark areas of the pictures. These two sets of modulated rectangular waves are combined forming an alternating current with rectangular alternations with variable widths. In series with this alternating current is a D. C. voltage which shifts the axis of the alternating current so that it is a pulsating D. C. voltage of the same general form. In series with this combination is a

sine wave of the same frequency and in phase with the rectangular alternating current, thus, the rectangular waves are extended farther from their common axis due to this increase in voltage. As the envelope voltage of this combined wave does not reverse, it can be used for modulating a radio frequency carrier wave. In this radio carrier wave will be the modulated rectangular waves of each picture and a synchronizing voltage. In this system the blacker the area scanned the greater the modulation. When two white areas are being scanned the alternations are not modulated, in this case the final wave is a pulsating sine wave.

15 Another new and novel feature of my invention resides in a receiver that will respond to the combined two sets of picture signals and a continuous synchronizing signal and can divide out each set of picture elements, for its own recorder and controls the recording of the shading of each picture and drives the recorder in synchronism with the transmitted picture.

20 The object of this invention is to provide a simple system for transmitting, receiving, recording and synchronizing two pictures at the same time.

25 Another object of this invention resides in the construction and the arrangement of the mechanical and electrical parts as will be understood from the following specification, in connection with the accompanying drawings which will illustrate one embodiment of my invention by way of example. In the accompanying drawings like reference numerals designate corresponding parts throughout.

30 Figure 1 is a schematic block diagram showing the general arrangement of the elements and amplifiers in this duplex facsimile system.

35 Figure 2 shows schematic layout of the circuit diagram of the duplex facsimile amplifiers.

40 Figure 3 shows the effect that shading of the pictures has on different parts of the amplifier.

45 Figure 4 shows the envelopes of the output of the amplifier for various types of voltages.

50 Figure 5 is a schematic block diagram showing the general arrangement of a duplex facsimile receiver.

55 Figure 6 shows the schematic layout of the receiver circuit diagram.

Figure 7 shows a modified form of a recorder for one picture with two recording elements.

Figure 8 is an example of a radio carrier wave, which contains the picture elements of the two pictures and a synchronizing frequency.

Figure 9 is a rectified signal of radio carrier waves shown in Figure 8.

Figure 10 shows the separate picture elements of both pictures.

Figure 11 shows the synchronizing voltage.

Figure 12 shows the plate current and plate voltage relationship of a pentode tube.

The general operating features of this duplex facsimile system are as follows:

The block diagram Figure 1 shows that synchronous motor drives two scanners and a high frequency generator. This generator supplies the high frequency keying voltage through two half wave rectifiers, one for each amplifier. One amplifier receives one alternation and the other amplifier receives the other alternation of the said keying voltage. The scanners pick up the light variations due to the shading of the picture elements and modulate the rectified keying alternations. The peaks of these alternations are suppressed to a low and equal value. The two sets of suppressed peaks are combined forming an alternating current, which is combined with a high frequency current from the generator of the same frequency and in phase with each other.

In Figure 2 the synchronous motor 1 drives the high frequency generator 2 and the two scanning drums 3 and 3'. The light from lamp 4 is focused by lens 5 on the revolving scanning drum 3 on which is mounted picture "A." The light from picture "A" is reflected into phototube 6 which is connected in series with the battery voltage 7 and the high resistance 8. The resistance 8 is connected between the grid 9 and the cathode 10 of the three element vacuum tube 11. An increase in the amount of light due to a white area of picture "A" reflected into the phototube 6 will cause an increase in the current through the resistance 8, and an increase in the negative voltage on the grid 9 of tube 11 and a decrease in the plate current 12. A black area on picture "A" will decrease the reflected light into phototube 6 and a decrease in the current through resistance 8 and a less negative voltage on the grid 9 of vacuum tube 11 which will increase conductivity of the plate circuit. In the plate circuit of tube 11 is the secondary winding 13 of transformer 14 which is connected to high frequency generator 2 and resistance 15 and battery voltage 16. The biasing voltage of tube 11 is so adjusted that when a white area of picture "A" is being scanned the tube 11 is biased to the cutoff point so that no current from the secondary 13 of transformer 14 will flow through the plate circuit. As the reflected light is reduced due to the scanned portion becoming darker the bias is reduced and the peak currents from secondary 13 will flow in the plate circuit. When the scanned portion is black the maximum peak current of one side of the high frequency wave is rectified. This modulated rectified half wave will flow through the resistance 15 and the voltage drop across resistance 15 will operate the amplifier tube 16. An increase in the plate current of tube 11 due to a dark area of picture "A" will cause a positive voltage increase on the grid 17 of tube 16. This will cause more current to flow in the plate circuit of tube 16 and a greater drop in voltage across the resistance 18. The pentode tube 19 is operated by the drop in voltage across resistance 18. The general operating characteristics of a pentode tube are shown in Figure 12, in this tube if the plate voltage is increased above a certain point the plate current does not increase to any extent. In series with the pentode tube 75

19 and the resistance 18 is resistance 20. When the peak voltage in resistance 18 increases beyond a certain value the plate current in tube 19 and through the resistance 20 will not increase any more, thus the voltage across resistance 20 will not increase for higher voltages across resistance 18. The voltage across resistance 20 is flat for these high values.

The lower amplifier in Figure 2 is constructed and operates the same as the upper amplifier that has just been described. Picture "B" is mounted on scanning drum 3'. Battery 21 is in the plate circuits of both tubes 19 and 19' and is so adjusted that plate current in both these tubes are near the knee of the curve shown in Figure 12, as both tubes have the same operating characteristics the voltage drop due to these continuous currents through resistances 20 and 20' will balance each other. The increase in currents in each amplifier due to dark picture elements of equal value will not balance out because one amplifier operates on one half of the waves and the other amplifier on the other half of the waves, from transformer 14. Resistance 20 which has the voltage variations across it that correspond to the picture elements of picture "A" and is connected in series with the resistance 20', which has the voltage variations across it that correspond to the picture elements of picture "B" but of opposite phase. These voltages across 20 and 20' combine and produce an alternating current 33 with varying alternation widths, and constant amplitude. This will be described later.

The transformer 22 which carries the synchronizing signal is connected to generator 2 and to the same frequency that operates transformer 14. The secondary 23 of transformer 22 is connected in series with resistances 20 and 20' so that the voltages across the resistance 20 are in phase with one half of the waves and the voltages across resistance 20' are in phase with the other half of the waves from secondary 23. The result is that the voltages of both alternating currents add together producing a very complicated wave form. In series with resistances 20 and 20' and secondary 23 is a battery voltage 24 which is used to make a pulsating D. C. voltage out of the combined alternating currents from resistance 20 and 20' and the synchronizing voltage of secondary 23. This pulsating D. C. voltage appears across the terminals 25 and 26 and can be used to modulate a carrier wave or be used to modulate the radio transmitter 27.

In Figure 3 the area 28 represents a shaded section of picture "A" going from white to black. The triangle 29 represents the voltage variation across the resistance 8 due to reflected light from the shaded section 28 and this voltage is applied to the grid 9 of tube 11. The A. C. wave 30 represents the keying voltage that is applied to the plate 12 of tube 11 from the secondary 13 of the transformer 14 which is connected to generator 2. The plate current that flows through resistance 15, due to the change in grid voltage and the A. C. voltage in the plate circuit, produces the voltage variations as shown in 31. For example the white area in 28 produces no voltage on the grid 17 of tube 16, the black area produces the maximum positive voltage while the shaded areas between integrate the voltages between zero and maximum. The voltage shapes shown in 31 are amplified to proportionately high peak values by the tube 16 with corresponding large voltage variations across resistance 18. These voltages are applied to the plate of the pentode

tube 19 which holds the plate current that flows through resistance 20 constant, when these voltages across resistance 18 reach a predetermined value. The result of this current control through resistance 20 is shown by the rectangular wave alternations shown in 32. In this case the peak voltages are constant and the width of the alternations are the same as the widths shown in 31. The light and dark areas of 28 are represented by the width of the rectangles shown in 32. The shaded area 28' produces the same general effect through the lower amplifier that the shaded area 28 did through the upper amplifier but in this case the shaded area 28' is reversed, that is the black area is scanned first and the white area last, so that the voltage in 29' decreases. The combined rectangular alternate voltages across both resistances 20 and 20' are shown in 33, the rectangular voltages above the line represent picture "A" and the rectangular voltages below the line represents picture "B."

The result of placing only the battery voltage 24 across the terminals 25 and 26 for a period of time is shown by the rectangular envelope 34 in Figure 4. The results of placing the battery voltage 24 and the A. C. synchronizing voltage 30 from secondary 23 across the terminals 25 and 26 are shown by envelope 35. The results of putting the voltage variations across the resistances 20 and 20' in series and in phase with the A. C. synchronizing voltage 30 from secondary 23 and the battery voltage 24 are shown by envelope 36. The high rectangular peak areas 36' represent the shaded picture elements of picture "A," the zero rectangular peak areas 36'' represent the shaded picture elements of picture "B," the curves in the center are part of the synchronizing voltage 30. If both the pictures "A" and "B" were white the rectangular portions 36' and 36'' of the envelope 36 would disappear and only the synchronizing wave 30 plus the battery voltage 24 would be left as illustrated in envelope 35.

The block diagram in Figure 5 shows the general arrangement of the duplex facsimile receiver and recorder. The incoming radio carrier wave is amplified and a part of this amplified signal is rectified and the different picture signals separated and amplified and recorded, respectively. Part of said amplified signal is rectified and the picture envelopes suppressed leaving only the synchronizing frequency which is amplified and operates a synchronous motor that drives the two recording drums.

A schematic circuit diagram of the receiver is shown in Figure 6 in which 40 represents the radio amplifier which is inductively coupled by transformer 41 to the full wave rectifier 42. The output of this rectifier tube 42 is connected across the fixed terminals of resistance 42a. For the sake of simplicity no filter circuit is shown in the output of the rectifier tube 42. The sliding contact 43 on resistance 42a is connected in series with the potentiometers 44 and 45, which is connected back to resistance 42a at point 46. The upper point of potentiometer 44 is connected to the positive terminal of battery 41, the negative terminal is connected to the grid 43 of tube 50, the lower point of potentiometer 45 is connected to the negative terminal of battery 51 and the positive terminal is connected to the grid 52 of tube 53. The cathode 54 of tube 50 is connected to the sliding contact 55 of potentiometer 44. The cathode 56 of tube 53 is connected to the sliding contact 57 of potentiometer 45. The plate 58 of tube 50 is connected to recorder 59

which reproduces picture "A" on drum 73. The plate 60 of tube 53 is connected to the recorder 61 which reproduces picture "B" on drum 72. The connecting point between the two potentiometers 44 and 45 is connected to plate battery 62, the other side of this battery is connected to both picture recorders 59 and 61.

The rectifier tube 63 is inductively coupled to transformer 41 by winding 64. The output of tube 63 is connected by pushpull transformer 65 to the plates of the pentode tubes 66 and 67. The output of these tubes is connected by the pushpull transformer 68 to the two power tubes 69 and 70 which operate the synchronous motor 71 which drives the two scanning drums 72 and 73 in synchronism with scanning drums 3 and 3' as shown in Figure 2. Scanning drum 72 carries the reproduced picture "B" and scanning drum 73 carries the reproduced picture "A."

If the two phototubes 6 and 6' shown in Figure 2 were scanning the same picture, one scanning point being ahead of the other, the same transmitting and receiving equipment could be used for transmitting and receiving one picture. The recording equipment would have to be changed, that is the two recording drums 72 and 73 would have to be replaced by a single drum 74 as shown in Figure 7, and the two recorders 59 and 61 would have to be spaced the same distance apart as the two scanning points.

The advantage of this system is that fading due to long distance transmission of the carrier waves would not affect the recording of the picture as much as in a single recording system because the chances of two fadings occurring at a definite time apart are small. If one phototube is sensitive to one color and the other phototube is sensitive to another color and the corresponding recorder reproducing these colors, it is possible to transmit a colored picture with this system. This system of transmission would be advantageous during war inasmuch as that planes could transmit a picture or information at twice the speed and if transmitted on two different radio wave lengths the chances of getting through would be many times greater because of the difficulty of interfering with both radio waves at the same time.

The envelope 36 shown in Figure 4 is used to modulate a radio carrier wave and will reproduce a radio frequency carrier wave envelope as shown in Figure 8. This radio wave is amplified by radio amplifier 40 shown in Figure 6 then it is rectified by rectifier tube 42. This rectified voltage is applied across the resistance 42a and has an envelope form as shown in Figure 9. The general voltage amplitude of this envelope is regulated by sliding contact 43 and is applied across the potentiometers 44 and 45. The positive voltage due to the drop in potential caused by the envelope voltage across the potentiometer 44 is regulated by the sliding contact 55 and is applied to the grid 43 of tube 50. The envelope voltage in Figure 9 would be reproduced again except for the battery voltage 47 biasing the grid 43 of tube 50 for values under the line 75 below the cutoff value of the tube. Thus, the rectangular value above the line 75 representing the dark areas in picture "A" is reproduced in the plate circuit of tube 50 which operates the recorder 59 which records the picture "A" on the synchronized drum 73. These picture elements represented by the variations in the plate current are shown by envelope 79 in Figure 10. The negative voltage due to the drop in potential caused by the envelope voltage shown

in Figure 9 across the potentiometer 45 is regulated by contact 57 is applied to the grid 52 of tube 53. The envelope voltage shown in Figure 9 applied across the potentiometer 45 would be bias tube 50 beyond the cutoff point, for all values except for the positive bias of battery 51 which is so adjusted for all values under the line 76 representing dark areas in picture "B" are reproduced in the plate of tube 53. Thus, the rectangular values under the line 76 are reproduced in the plate circuit of the tube 53 which operates recorder 61 which records the picture "B" on the synchronized drum 72. These picture elements represented by the variations of plate currents are shown in envelope 80, Figure 10.

In this system of transmitting two pictures simultaneously, by the breaking up of each picture into picture elements, by means of the alternations of a keying frequency, it is obvious when one picture element is being transmitted from one picture the corresponding picture element of the other picture is suppressed, thus, every other picture element of each picture is transmitted. The size of the picture element is determined by the frequency of the keying voltage.

The tube 50 operates on the value of the positive voltage above the line 75 and tube 53 operates on negative voltage below the line 76. In other words tubes 50 and 53 operate on the dark or shaded elements, the amount of shading depends upon the width of the rectangular waves, shown in picture 10. When a white area is being scanned in picture "A," as shown in Figure 2, no signal will appear above the line 75, and when a white area is being scanned in picture "B" no signal will appear below the line 76. The only signal that will come through under the above conditions will be the synchronizing voltage that operates within the lines 75 and 76 which will not operate either of the tubes 50 or 53.

The synchronizing voltage is picked up by coil 64 and operates the rectifier tube 63. The result of this rectification is shown by envelope in Figure 9. This rectified voltage is applied to the plates of the two pentodes 66 and 67 by the transformer 65. After going through the transformer 65 the axis of the envelope is shifted from line 77 to line 78. This modulated A. C. wave is applied to the plates of tubes 69 and 70 which are adjusted so that values above 75 will not go through the tube 66 and values below 76 will not go through tube 67. The wave in the primary winding of transformer 68 will look like Figure 11 which corresponds to Figure 9 with the rectangular voltage extensions removed. Figure 12 gives the plate voltage and plate current curve for pentodes tubes. The tubes 66 and 67 are so adjusted that when the plate voltages have reached values corresponding to the line 75 and 76, the tubes have reached the knee of the curve as shown in Figure 12 and for voltages above this point there is little if any increase in the plate current. The resulting wave is not a sine wave but it can be improved by transformer 68 or by using a filter before applying the voltages to the power tubes 69 and 70 which operates and keeps

the synchronous motor 71 in step with the frequency from generator 2 as shown in Figure 2 so that the drums 72 and 73 operate in synchronism with the scanners 3 and 3'.

5 I have chosen the particular embodiments described above as illustrative of my invention, and it will be apparent that various other modifications may be made without departing from the spirit and scope of my invention, which modifications I aim to cover by the appended claims.

I claim as my invention:

1. A method of transmitting two shaded pictures simultaneously adding a constant amplitude variable time duration keying impulse cor-

15 responding to the shading intensity of one picture to one half of the alternations of a synchronizing signal, adding a constant amplitude variable time duration keying impulse corresponding to the shading intensity of the other picture to the other half of the alternations of the said synchronizing signal, combining all said signals and impulses, and modulating a carrier.

2. A two picture radio carrier wave synchronizing transmitting system, comprising means for

25 generating a synchronizing signal, means for adding to one half of the peaks of the said synchronizing signal a constant voltage keying signal whose width varies as the shading intensity of the scanned picture, a means for adding to the other half of the peaks of said synchronizing signal a constant voltage keying signal whose width varies as the shading intensity of a second scanned picture, means for modulating a radio carrier wave with the combined said synchronizing signal and the two said picture keying signals, and applying said signals for synchronizing and simultaneously recording said pictures.

3. A method of transmitting two independent and separate shaded pictures alternately, comprising generating a sustained synchronizing signal,

40 separating the positive and negative alternations, keeping the amplitude constant and controlling the duration of the said positive and negative alternations with the shading of the said separate pictures, generating a radio carrier, applying controlled alternations so that the positive alternation effects only an increase in the amplitude of the said radio carrier and the negative alternation effects only a decrease in the amplitude of the said radio carrier.

4. A method of transmitting two shaded pictures which comprises generating a synchronizing wave, modulating separately the positive and negative alternations of the said synchronizing wave in accordance with the variations of the light intensities from the said two shaded pictures, using the said modulated alternations to control the duration of picture signals, the amplitude of said picture signals remaining constant, adding the said picture signals to corresponding alternations of said generated sine wave, modulating a transmitter carrier with both the said synchronizing wave, and the said synchronizing wave plus the said picture signals.

RAYMOND R. HAUGH.
